THERAPEUTIC DEVICE

Paul F. Tunke, Ridgewood, N. Y.

Application December 3, 1941, Serial No. 421,494

2 Claims. (Cl. 128—254)

The present invention relates primarily to a therapeutic device and more especially to such a device for applying cold to the eyes and adjacent facial areas of a human body.

It has been found that the application of a cold or a cooling substance to tired and aching eyes or the immediately adjacent parts of the face has a soothing and resting effect on the eyes. Heretofore devices have been provided to cool the eyes such as by circulating cooled or iced water through applicators applied to the eyelids and/or adjacent facial areas for resting and soothing the eyes. While such devices have been found to be helpful in producing the desired effect, most have the disadvantage of being cumbersome and some require inlet and exhaust means such as tubes for the circulating fluids. Prior devices also have among others the disadvantage of hindering and limiting the movement of the person to whose eyes the device is applied, and they are expensive.

Accordingly, it is one of the primary objects of the present invention to provide a device of the above mentioned type which has none of the enumerated objections and which may be applied and held in place over the eyes of a person without requiring the person to remain in any one fixed or relatively fixed position.

Another object of the invention is to provide a device of the above type which is a self-contained unit in that no external connections thereto are required for circulating and such purposes.

Still another object of the invention is to provide a device of the above type which is light in weight and which has sections that contact the eyelids and adjacent facial areas which is of soft and absorbent material so as to assume the contour of the area to which the device is applied and establish a reasonably good contact between the device and the area to which it is applied.

Still another object of the invention is to provide a device which will hold crushed ice so that the melting thereof absorbs heat from the parts of the body to which the device is applied.

Still another object of the invention is to provide a device which gives the person upon whom the device is applied a feeling of applying a damp or wet surface to the eyelids while at the same time preventing the escape of water formed by the melting ice in the device.

Still another object of the invention is to provide a device of high thermal efficiency in which the minimum of cold is lost from the melting of the ice and the major portion thereof is trans-

ferred to the area to which the device is applied.

The above and further objects of the invention will be more apparent in the following detailed description thereof when taken in conjunction with the accompanying drawing, in the latter of which:

Fig. 1 is a plan view of a device constructed in accordance with the present invention;

Fig. 2 is a front elevational view of the device;

Fig. 3 is a sectional view of one of the units of the device taken substantially on line 3—3 of Fig. 2; and

Fig. 4 is a view partly in section of a modified arrangement of one of the units of the device.

Referring to the drawing and particularly Figs. 1 to 3, which shows a preferred form of the invention, the device comprises two units, indicated generally by reference numerals 11, of such a size that they may be applied to and fitted over the eyes of a person to completely cover the eyes or eyelids and the immediate adjacent facial areas. Each unit comprises a somewhat cup-shaped hollow container 12 with substantially straight sides which terminate in rims 15. In the preferred embodiment of the invention, the containers 12 have formed integrally therewith radially extending arms 13. The arms 13 are joined together by some means such as by a rivet 14 whereby the two containers 12 are pivotable with respect to one another. The length of the arms 13 is such that the centers of the containers 12 are separated by a distance substantially equal to the distance between the center of the eyes of an average person.

Also formed integrally with the containers 12 on substantially opposite sides to the arms 13 are lugs 16. The lugs 16 are preferably formed near the inner extremities or rims of the containers 12 and have holes therein which permit the ready attachment thereto of a holding means such as an elastic band 10. The elastic band 10 is arranged so as to be passed around the back of the head of the person to whom the device is applied to hold the device in place over the eyes

45 while at the same time permitting movement of the person.

In the preferred embodiment the containers 12 are made of some plastic material such as catalin which permits moulding or casting of the arms 13 and lugs 16 integrally with the main container portion. However, numerous other suitable materials may be employed and the arms 13 and lugs 16 may be made separate and attached to the containers 12 by suitable means such as riveting.

As more clearly shown in Fig. 1, the upper open ends or the rims 15 of the containers 12 instead of being cut straight across perpendicular to the central axis of the container, are cut at an angle to more nearly conform to the contour of the eyes of a person to whom the device is applied. Secured to the rims of the containers 12 by glueing or other suitable means are oval-shaped pads 17. The pads 17 are somewhat larger than the outer diameter of the containers 12 and accordingly extend a substantial distance beyond the outside rims of the containers. The pads 17 are preferably composed of sponge rubber or other suitable light porous material of soft construction which permits easy flexing thereof.

The thickness and diameter of the pads 17 are such that they are capable of absorbing a quantity of water substantially equal to the volume of the containers or a substantial portion of the water formed from ice 25 that may be placed in the containers 12. Holes 18 are formed in the ends of each of the containers 12 to permit the placing of crushed or cracked ice in the containers. The holes 18 are above the center of the containers, as shown in Fig. 2, so as to prevent the leakage of water from the melting of the crushed ice therefrom when the device is applied to a person in an upright position, the device being substantially in the position shown in Fig. 2 when applied to a person in an upright position.

The device is designed primarily for use on a person in a prone position or with the head tilted backward. However, the arrangement of the device and the holes 18 therein is such that the position of the person to whom the device is applied is not critical and may be applied to a person with the head held upright.

When the containers 12 are filled or partly filled with crushed ice and the device applied to the eyes of a person, the soft sponge rubber pads 17 assume the contour of the eyelids and the immediate surrounding facial areas. The water from the melting of the ice in the containers 12 permeates the pads 17 and gives the effect to the wearer of a damp or wet pad being applied to the eyelids. The heat absorbed by the water in the pads 17 is conveyed to the ice and water within the containers to melt more of the ice. The moisture in the pads serves as a good conductor of heat and cold to and from the areas to which the device is applied and the temperature of the surface of the pads in contact with the facial areas may be substantially that of the ice water within the containers.

The pads, as hereinbefore stated, are of such thickness and size as to be capable of absorbing substantially all the water from the ice that may be placed in the containers, and this prevents the leakage of the water from the device during the normal use thereof while at the same time permitting a damp or wet contact with the facial areas to which the device is applied.

Fig. 4 shows a modification of the invention wherein a unit 20 includes a container 19 which may be made from a section of tubing or a cyl-

inder. The outer end of the container is closed by means of a tight fitting cap 21. The cap 21 is preferably of rubber and forms a substantially watertight cover over the outer end of the container 19. In other respects the unit shown in Fig. 4 is substantially similar to either of the units 11 shown in Figs. 1 to 3, it including on the inner rim of the container a pad 22, a connecting arm 23, and a lug 24 to which is attached a resilient band 26.

It is obvious that various other modifications of the invention shown and described herein may be made without departing from the spirit or essential attributes of the invention, and it is desired, therefore, that only such limitations be placed thereon as are imposed by the prior art or are specifically set forth in the appended claims.

What is claimed is:

1. A therapeutic device of the type described comprising a pair of substantially flat and circular, soft, porous and absorbent pads adapted to be applied to and substantially cover a patient's eyes, hollow fixed and cup-shaped containers attached at the rims to one side of said pads for holding cracked or crushed ice in contact with one side of said pads, openings in said containers for inserting said ice therein, said openings being so located as to prevent the escape of ice or water from said containers when said device is applied to the patient in a prone or upright position, arms extending from said containers pivotally connected whereby said containers and said pads are spaced apart and pivotally movable relative to each other, means including said pivotal connection whereby said containers are pivotable upon an axis substantially perpendicular to the central axis of said containers and means including said pads to convey heat from the areas to which they are applied to said ice to melt the same and to absorb the water of the melted ice.

2. A therapeutic device of the type described comprising a pair of substantially flat circular soft, porous and absorbent pads adapted to be applied to and substantially cover a patient's eyes, hollow fixed and cylindrically shaped containers attached at the rims of one end thereof to one side of said pads for holding cracked or crushed ice in contact with one side of said pads, openings in said containers for inserting said ice therein, removable covers for said openings, means including said covers for closing the opposite ends of said cylindrically shaped containers for preventing the escape of water or ice from said containers through said openings, arms extending from said containers pivotally connected together whereby said containers and pads are spaced apart and pivotally movable relative to each other, means including said pivotal connection whereby said containers are pivotable on an axis substantially perpendicular to the central axis thereof and means including said pads and water from melted ice in said containers to convey heat from the areas to which said pads are applied.

PAUL F. TUNKE.
